his Attorney.

UNITED STATES PATENT OFFICE.

CLEMENS E. EHNBORN, OF CHICAGO, ILLINOIS.

SPOOL.

1,319,381.

Specification of Letters Patent. Patented Oct. 21, 1919.

Application filed October 29, 1918. Serial No. 280,093.

To all whom it may concern:

Be it known that I, CLEMENS E. EHN-BORN, a citizen of the United States, and a resident of the city of Chicago, county of Cook, and State of Illinois, have invented certain new and useful Improvements in Spools, of which the following is a specification.

My invention relates to improvements in spools, and has for its object the provision of an improved spool for thread, or the like, which is strong and durable in use and capable of economical production.

Other objects will appear hereinafter.

15 The invention consists in the combinations and arrangements of parts hereinafter described and claimed.

The invention will be best understood by reference to the accompanying drawings 20 forming a part of this specification, and in which,

Figure 1, is a section taken through one end of a spool embodying the invention,

Fig. 2, an end view of the same,

25 Fig. 3, a section taken through one of two end flanges employed in the construction and shown before the same is secured in place, and

Fig. 4, a detail section of one end of a 30 central hub employed in the construction.

The preferred form of construction, as illustrated in the drawings, comprises a central hub 5, of wood or like material, having the usual central bore 6, and provided at 35 each end with an outwardly flaring conical projection 7 somewhat smaller than the body of hub 5 and arranged with the smaller end of the cone adjacent the hub. End flanges are secured to each end of said 40 hub to complete the spool. Each of these end flanges consists of a sheet metal stamping 8 having an outwardly extending peripheral lip or flange 9 and a central hub 10 provided with a central opening 11, said 45 hub being of a size to pass freely over the corresponding projection 7 and opening 11 registering with bore 6 to continue the same. Each of the end flanges 8 is also provided with radiating beads or corrugations 12, 50 which, in conjunction with lip 9 and hub 10 serve to stiffen and strengthen the construction.

In assembling the spool, one of the end flanges 8 is secured over each of the projections 7 at the ends of the hub 5. This is 55 done by passing the central hub 10 over the projection 7, and then spinning the periphery of said hub down into close and tight engagement with the periphery of the projection, also forcing the parts into snug 60 engagement with shoulder 14 of the hub 5. In such spinning, beads or depressions 13 are formed in the periphery of hub 10 and are thus impressed into the periphery of the corresponding projection 7, thus preventing 65 turning of the end flange with reference to the body of the spool. In this way spools, which are strong and durable in use, may be provided with great economy.

While I have illustrated and described 70 the preferred form of construction for carrying my invention into effect, this is capable of variation and modification without departing from the spirit of the invention. I, therefore, do not wish to be limited to the 75 precise details of construction set forth, but desire to avail myself of such variations and modifications as come within the scope of the appended claims.

Having described my invention, what I 80 claim as new and desire to secure by Letters Patent is:—

1. A spool comprising a hub of wood or the like, having a conical projection at each end arranged with the smaller end of the 85 cone adjacent the hub; and sheet metal flanges placed over and spun onto said projections, substantially as described.

2. A spool comprising a hub of wood or the like, having a conical projection at each 90 end arranged with the smaller end of the cone adjacent the hub; and sheet metal flanges placed over and spun onto said projections, there being beads formed in such spinning and impressed into such projections, substantially as described.

3. A spool comprising a hub of wood or the like, having a conical projection at each end arranged with the smaller end of the cone adjacent the hub; and flanges secured 100 to said projections, each of said flanges consisting of a sheet metal stamping having a peripheral lip or flange and a central hub fitting over the corresponding projection.

said central hub being spun into snug and
close engagement with said projection, there
being beads formed in such spinning and
impressed into said projection, substantially
5 as described.

In testimony whereof I have signed my

name to this specification in the presence of
two subscribing witnesses.

CLEMENS E. EHNBORN.
